UNITED STATES PATENT OFFICE.

MICHAEL J. McNAMARA AND FREDERICK E. CANTNER, OF PHILADELPHIA,
PENNSYLVANIA.

DESIGN FOR A BASIN-SUPPORTING BRACKET.

40,400.

Specification for Design.

Patented Dec. 14, 1909.

Application filed September 13, 1909. Serial No. 517,505. Term of patent 7 years.

To all whom it may concern:

Be it known that we, MICHAEL J. McNAMARA and FREDERICK E. CANTNER, citizens of the United States, residing at Philadelphia, in the county of Philadelphia and State of Pennsylvania, have invented a new, original, and ornamental Design for Basin-Supporting Brackets, of which the following is a specification, reference being had to the accompanying drawing, forming part thereof.

Figure 1, is a top plan view, and Fig. 2, is a side elevation showing our new design. We claim:

The ornamental design for a basin supporting bracket, as shown.

MICHAEL J. McNAMARA.
FREDERICK E. CANTNER.
